UNITED STATES PATENT OFFICE.

BENJAMIN SCHECHTER, OF NEW YORK, N. Y.

AUXILIARY BED.

1,168,680.

Specification of Letters Patent. Patented Jan. 18, 1916.

Application filed January 22, 1915. Serial No. 3,755.

To all whom it may concern:

Be it known that I, BENJAMIN SCHECHTER, a citizen of the United States, and resident of the borough of Brooklyn, county 5 of Kings, city and State of New York, have invented certain new and useful Improvements in Auxiliary Beds, of which the following is a specification.

The device, the subject of this invention, 10 is intended to perform all of the functions of an ordinary bed or crib, but I have termed it an auxiliary bed for the reason that it is my intention that it shall be adapted to and become a part of an ordinary bed, and that 15 although it may not be self-supporting as an independent unit, I show it secured to an ordinary bed in a manner that I shall describe.

It shall furnish a firm and reliable support for the necessary bedding and for a 20 child of almost any age or size.

I have found that it is particularly advantageous to arrange a child's crib connected in close proximity to an ordinary bed 25 so that when required the child can receive any necessary attentions not only quickly but with little inconvenience to the person whose duty it may be to administer to the wants of the child. I have also found 30 that under certain conditions, particularly in large cities where the size of the apartment does not afford extended space for the arrangement of beds, that it is advantageous to provide a crib or small bed for a child in 35 such a manner that the space that it shall occupy shall be reduced to the smallest possible area when the crib is not in use, and that when the crib is not in use it may be folded or stored or otherwise disposed of so 40 that the space that would otherwise be devoted to it may be used for other purposes.

Such a device is the subject of this invention and in its development I shall endeavor to provide a means of easy operation, 45 a simple construction, and also a mechanical device that shall be sanitary even to the greatest degree.

The following is what I consider the best means of carrying out this invention, and 50 the accompanying drawings form a part of this specification, in which:

Figure 1 shows the completed device in position to be used. Fig. 2 shows the device in the position which it will be caused to as-

sume when not in operation. Fig. 3 is a 55 detail of a part of the supporting means.

Similar reference numerals indicate like parts in all the figures where they appear.

From the drawing it will be observed that my device is operable in conjunction with 60 and that it is partly supported by, an ordinary bed. Such a bed may consist of what is usually termed the head and foot supports as indicated at 1 and 2, the side rails as indicated at 3 and 4, and the spring as indicated at 5, which should be supported upon the side rails 3 and 4 by means of foot pieces 6 and 7. The spring may be of any ordinary construction, but in the drawing I have indicated the woven wire spring, provided 70 with side rails 8 and 9, upon which the spring wires are secured, and which serve as distenders to keep the wires tightened to a desirable degree.

The elements thus far described may be 75 of ordinary construction and ordinary shape and size, and the particular design of the springs and their method of operation does not limit or affect my invention, and therefore I will not find it necessary to describe 80 these parts or their construction more fully than I have already done.

Secured to the side rails 8 and 9 of the spring and extending between these parts, and transversely across the bed is a bar 10 85 provided with a slot 11. This bar may be clamped to the under side of the side bars 8 and 9, or it may have its end turned to engage this bar.

Through the slot 11 I arrange a bolt 12, 90 and upon this bolt a wing-nut 13 will be screw-threaded. The bolt 12 and nut 13 engage and support a metal strap 14 which has its outer or free end 15 secured to a bar 16. This bar is the inner cross-bar of my 95 auxiliary bed or crib.

A bar 17 similar to the bar 16 extends parallel thereto and at a predetermined distance therefrom, and these bars are held predetermined distances apart by a head and 100 foot bar, as shown at 18 and 19, respectively.

The bars 18 and 19 extend inward for a short distance beyond the side bar 16, and on the under side of their innermost projecting end each of the bars 18 and 19 are provided with a slot 20; each of the slots being transverse to the longitudinal axis of

their respective bars are free to engage upon the adjacent side bar 3 of the bed.

In each of the bars 16 and 17, and near the ends thereof, I produce perforations as indicated at 21 and 22, and through these perforations I may extend a rotatable rivet. Upon each pair of rivets I secure the lower end of the foldable though normally upwardly projecting head and foot frames as indicated at 23 and 24. In use these frames project upward as shown in Fig. 1 and assist the side frame 25 which is pivotedly supported by the end bars 18 and 19, in insuring that the occupant of my bed cannot accidentally fall therefrom. When however the bed is not in use the ends 23 and 24 fold inward upon the bedding and the side frame 25 folds downward onto the end frames 23 and 24.

Pivoted to the outer side bar 17 I provide supports 26 and 27 which when not in use will occupy the position shown in dotted lines in Fig. 2, but when opened downward as shown in Fig. 1 these supports materially assist in firmly supporting the crib.

From the position of the bar 10 and the length of the slot 11 therein it will be understood that the crib may be arranged on either side of the bed, and it will also appear obvious that the bar 10 may be arranged upon the side bars 8 and 9 anywhere between their ends.

When the crib is in use the position of it will be as shown in Fig. 1 but when it is no further desired the ends 23 and 24 are folded inward, the side frame 25 downward thereon, the legs or supports 26 and 27 upward, and then a slight lifting of the inner ends of the top and bottom bars 18 and 19 will allow the crib to be slid inward and this will cause the bolt 12 to travel in the slot 11. The inward motion is continued until the lug 28 reaches the outer surface of the side bar 3 of the bed; this side bar will then support the side bar 17 of the crib. To withdraw the crib, the lug 28 or the side bar is pulled outward causing the end bars 18 and 19 to slide upon the side bar 3 of the bed. When the outward motion is continued to the full extent the spring 30 arranged upon the bolt 12 forces the member 14 downward, which will cause the slots 20 in the end bars 18 and 19 to engage with the side bar 3; the

legs or supports 26 and 27 are opened downward, the head and side frames upward and my device is ready for use.

I may omit the spring 30 with its loss of function depending upon gravity to cause the engagement of the slots or I may make the member 14 a spring member with a tendency to force the bar 16, upon which it is engaged, downward.

The shape, style and size of my crib may be changed or modified at will and other modifications may be made within the scope of the appended claims without departing from the principle or sacrificing the advantages of this invention.

Having carefully and fully described my invention what I claim and desire to secure by Letters Patent is:

1. An auxiliary bed having end and side frames in combination with a slotted bar secured to the springs of an ordinary bed, and a resilient and sliding connection between said slotted bar and said auxiliary bed for the purpose set forth.

2. An auxiliary bed having side and end bars, slots in said end bars, and means for depressing said slots for engagement with the side bars of a bed in combination with a slotted bar adjustably engaged with the springs of a bed and adapted to support said auxiliary bed when in a non-operative position.

3. An auxiliary bed having in combination, end bars provided with slots, a slidable support, and a resilient means for engaging said bars upon the side bar of a bed as and for the purpose set forth.

4. An auxiliary bed having in combination with an ordinary bed a slotted cross-bar adjustably secured thereto, a side bar, a spring depressed slidable connection between said adjustable bar and said auxiliary bed, and means for disconnecting said auxiliary bed, allowing it to be differently positioned in relation to said bed as and for the purpose set forth.

Signed at New York city, New York, this 4th day of January 1915 in the presence of these two witnesses.

BENJAMIN SCHECHTER.
